GAS CONVERSION PROCESS

Henry George Ellert and Charles Newton Kimberlin, Jr.,
Baton Rouge, La., assignors to Esso Research and
Engineering Company, a corporation of Delaware
Filed June 21, 1960, Ser. No. 37,781
6 Claims. (Cl. 260—676)

The present invention relates to the conversion of light hydrocarbon gases, and in particular to hydrocarbon gases having no more than four carbon atoms, to valuable liquid hydrocarbons suitable as fuel and chemical intermediates. More particularly, the present invention relates to the conversion of low molecular weight hydrocarbon gases to higher molecular weight valuable hydrocarbons in the presence of a hydrogen fluoride comprising catalyst. In a particular preferred embodiment, the present invention relates to the conversion of low molecular weight saturated hydrocarbons such as butane into a liquid, non-aromatic hydrocarbon product boiling in the heavy naphtha and middle distillate range.

In Serial No. 856,392, filed December 1, 1959, of which the present application is a continuation-in-part, it was disclosed that the treatment of paraffinic hydrocarbons having five or more carbon atoms with hydrogen fluoride in the vapor phase at high temperatures and in the further presence of a high surface area contacting agent, such as activated carbon, resulted in good yields of a highly aromatic product boiling in the middle distillate range. Thus, light naphthas boiling in the C₅/C₆ range, heptane, dodecane and cetane, when treated with gaseous anhydrous HF in the vapor phase in the presence of activated carbon at temperatures of about 900° to 1000° F., all gave high yields of C₇—C₂₀ alkylated aromatics. Under the same reaction conditions but in the absence of the char, no reaction product was obtained.

It has now been found that when lower molecular weight hydrocarbons, i.e. butane and lower, are contacted under the same reaction conditions with the same catalyst system, there is obtained in good yields a liquid hydrocarbon product having approximately the same number of carbon atoms as that obtained from the C₅—C₆ feed streams but substantially non-aromatic.

The conversion of hydrocarbons with hydrogen fluoride is well known. It is normally carried out in the liquid phase, either with aqueous or anhydrous acid and with or without catalyst promoter, such as BF₃, to give a variety of products. In the vapor phase, however, little or no reaction occurs with light hydrocarbons of the nature specified.

It is, therefore, the principal object of the present invention to set forth a novel process for converting low molecular weight paraffinic hydrocarbons into middle distillates in good yields and with little secondary reaction product.

It has now been found that these objectives may be achieved by contacting hydrocarbon streams of the nature hitherto described in the vapor phase with vaporized hydrogen fluoride in the further presence of a high surface but otherwise inert contacting agent at elevated temperature. The reaction is carried out at a temperature of about 600° to 1300° F. and 700° to 1200° F. or, preferably 750° to 1150° F., when processing paraffinic feeds, and the preferred contacting agent is high surface area char or other activated carbon. In the absence of the high surface area support, substantially no reaction is obtained, while in the presence of the carbon, good yields of middle distillate are obtained.

The distinction between this conversion technique and that of conversion by treating with liquid HF is best understood by considering the conversion of a butane stream.

2

It is well known, for example, that butane is isomerized by liquid HF. Thus, at about 100° to 400° F. using from 0.5 to 5 weights of HF based on butane feed, and under the developed pressure of the system, n-butane is converted to a near thermodynamic distribution of the two isomers. While the conversion is generally selective, overly severe process conditions can lead to some cracking. The formation of trace amounts of tar, called conjunct polymer and consisting of very high molecular weight, highly unsaturated cyclic species, may accompany cracking conversion. In contrast, vapor phase treatment of n-butane with HF in the presence of a porous contacting agent such as activated carbon (1) gives negligible isomerization, (2) produces liquid hydrocarbons in good selectivity, (3) said liquid hydrocarbons consisting mainly of acyclic monoolefins which are substantially lower in molecular weight and substantially less hydrogen deficient than the conjunct polymer obtained in liquid phase treatment.

Although any mixture of low molecular weight paraffinic hydrocarbons having no more than four carbon atoms may be employed, the present invention is most readily illustrated by showing the treatment of a butane stream. In the accompanying drawings, there is represented a preferred modification for carrying out the basic reaction in FIGURE 1, while FIGURE 2 is an embodiment designed to prepare high quality jet and diesel fuel.

Turning now to FIGURE 1, a feed of the type described above is passed through line 2, vaporized in heater 4 and the heated vapor passed into reaction vessel 6. Similarly, gaseous hydrogen fluoride is passed via line 8 into reactor 6. The latter is packed with highly porous, non-reactive contacting agent, preferably activated carbon. By non-reactive is meant those agents that will not react with HF. Besides carbon, amorphous calcium fluoride, magnesium fluoride and similar compositions may also be employed. The hydrogen fluoride to hydrocarbon feed ratio is about 0.1 to 4.0, preferably 0.5 to 2. The liquid hourly space velocity is maintained at from 0.2 to 4.0 v./v., depending upon the temperature and the acid to hydrocarbon ratio. The temperature within reactor 6 may be from 600° to about 1300° F., and preferably 850° to 1150° F. Pressure is atmospheric or slightly above.

The reaction mixture comprising reactants, catalyst and reactor products is passed via line 10 to condensation vessel 12. Any low molecular weight hydrocarbon gases formed during the reaction as well as unreacted gases may be recycled to the reactor via line 14. This recycle has the effect of decreasing dry gas make in the reaction. Similar effects may be realized by recycling a portion of the desired hydrocarbon product.

The condensed product may then be passed to settler 18 via line 16. HF may then be separated and recycled via line 20 and be revaporized. Alternately, only the liquid product is condensed, and the HF, gaseous products and unconverted feed are recycled as a gas stream. The desired hydrocarbon product is recovered via line 22 and may be freed from acid contaminants by washing, caustic scrubbing, and the like, followed by a distillation step.

The embodiment shown in FIGURE 2 is especially attractive for use in many areas where light hydrocarbons are in over-supply while heavier fuels, particularly jet and diesel fuels, are in high demand. In accordance with this embodiment, the olefinic fuel produced in the reaction is subsequently hydrogenated, preferably in part at least by the hydrogen formed during the reaction to improve the burning characteristics and produce a high quality, high density diesel or jet fuel.

Turning now to FIGURE 2, a light hydrocarbon feed is passed via line 30 into reactor 32, packed with active carbon. Hydrogen fluoride is admitted via line 58. Re-

action conditions within 32 are temperatures of 850° to 1200° F., hydrocarbon space velocity of 0.5 to 2 v./v./hr., 0.1 to 2.0 HF/oil ratio (weight) and a pressure of atmospheric to 400 p.s.i.g. When elevated pressures are employed, somewhat more severe reaction conditions are employed to offset the retarding effects of pressure on reaction rates. High pressures are, however, beneficial in another respect as indicated below.

The reactor effluent is then passed via line 34 to partial condenser 36 where products heavier than the feed are withdrawn via line 38 and passed to hydrogenation zone 40. The remainder of the reactor effluent is withdrawn through line 42, condensed, and passed to settler 44. Unconverted feed and some lower hydrocarbons are recycled to reactor 32 via line 47. A hydrogen-rich stream is withdrawn overhead from settler 44 and, in the case of a previous high pressure operation in reactor 32, it is passed directly to hydrogenator 40 via lines 54 and 55. If a low pressure operation is employed in 32, the hydrogen-rich stream may be passed via line 48 to compressor 50 for compression up to 200 to 400 p.s.i.g. From settler 44 acid is recycled to the reactor via line 46.

The product from the reactor, which may boil in the range of 200° to 600° F., is then recombined with the hydrogen at, for example, 200 to 400 p.s.i.g. and 500° F., using a platinum catalyst, in hydrogenator 40, which is of conventional design, and a high quality product boiling in the kerosene range is recovered. If desired or necessary, auxiliary or supplementary hydrogen may be supplied through line 57.

Though the process has been described in connection with a fixed bed of contacting agent, the latter may be present in the form of a bed of finely divided fluidized solids or a moving bed. Furthermore, it may be desirable to add a promoter to the active carbon. Suitable promoters are groups II, III, and VIII metals, metal oxides and metal fluorides, in concentration of 0.1 to 20 wt. percent of the carbon. Similarly, it may be desirable to add promoters to the hydrogen fluoride, such as BF_3 , small amounts of water or both.

The carbon gradually loses activity and selectivity with time, and reactivation is required. The latter may be accomplished by feeding superheated steam continually or intermittently to the carbon bed. While this may be done in a single vessel system, best results are obtained in a two vessel system such as employed in conventional fluid solids units. In this case, reaction is carried out in one vessel, regeneration in the other at somewhat higher than process temperatures, e.g. 1400° to 1600° F., as against 900° to 1200° F.

The advantages of operating in accordance with the present invention may be further seen and illustrated by the following specific examples.

The substantial unreactivity of hydrocarbons to vaporized HF in the absence of a support, or in the presence of a support not having an active surface, is shown in Example 1 below.

EXAMPLE 1

(a) A mixture of 2.9 parts of anhydrous HF and 1 part by weight of normal dodecane were passed through an empty Monel tube at 0.4 total hourly space velocity and 920° F. Less than 5% conversion to gas was obtained and the recovered liquid was essentially pure dodecane.

(b) Similar experiments were made with dodecane feed in which the reactor was packed with Monel gauze and copper shot.

Packing	Monel Gauze	Copper Shot
Temperature, ° F.	962	951
HF/oil Wt. Ratio	1.3	1.5
Total v./v./hr.	0.7	0.8
Conversion, Wt. percent	<5	<5

Again negligible conversion was obtained and the recovered liquid was essentially unconverted dodecane.

EXAMPLE 2

5 The utility of the process for upgrading and converting normal butane into middle distillate is shown below.

(a) A mixture comprised of 1.11 weights of anhydrous HF and 1 weight of n-butane is passed at 1100° F. and 612 total gas velocity through a bed of activated carbon. Butane conversion is 29.6% and the yield of liquid hydrocarbons is 11.4%. The liquid product consists mainly of $\text{C}_{10}/\text{C}_{20}$ acyclic monoolefins and is suitable for use as a distillate fuel or a chemical intermediate. Other products are hydrogen and a mixture of methane and C_2/C_3 olefins and paraffins. Only trace amounts of isobutane are found in the product.

(b) While a range of temperatures may be employed, under reasonable conditions of holding time and HF/oil ratio, temperatures around 800° F. and below give impractically low conversions. For example, an HF/butane mixture (1.57 HF/ C_4H_{10} wt. ratio) is passed at 800° F. and 573 total gas velocity through a bed of activated carbon. Conversion is only 2.0 wt. percent, the liquid product yield being 0.5 wt. percent.

(c) Holding time, as established by total gas space velocity, may be varied over a wide range, though excessive holding time results in degradation of the liquid product. For example, at 1100° F. and 1.5 HF/butane weight ratio, selectivity to liquid products is only 2.2 wt. percent at 36 v./hr./v. vs. 41.8 wt. percent at 550 v./hr./v.

EXAMPLE 3

Autoclave treatment of butane with anhydrous, liquid HF (3 HF/ C_4H_{10} weight ratio, 225° F. for 2 hours) gives some isomerization, a trace amount of cracked products, but little if any heavier product. To distinguish further vapor phase HF conversion in the presence of activated carbon from the liquid phase reaction, butane was treated with liquid HF promoted by BF_3 . In this experiment, 102 grams of butane and 304 grams of liquid HF were sealed in a 1 liter autoclave. The autoclave was then pressured to 200 p.s.i.g. with BF_3 and heated 2 hours at 225° F. The developed pressure was 1000 p.s.i.g. Even under these severe conditions, no liquid products similar to those formed in the vapor phase reaction were isolated. The products were isobutane, gas and a small amount (less than 1%) of tar.

EXAMPLE 4

Conversion of Propane to Liquid by HF Vapor-Activated Carbon Catalyst

A mixture of propane and anhydrous HF (0.88 HF/ C_3H_8 wt. ratio) was passed through a bed of activated carbon at 1100° F. and 1353 gaseous hourly space velocity (0.5 w./hr./v.). About 9% conversion resulted, and isopentane was obtained in 13.3% selectivity.

What is claimed is:

1. A process for converting paraffinic hydrocarbons consisting essentially of butane into higher liquid monoolefin hydrocarbons which comprises contacting said butane in the vapor phase in a conversion zone at a temperature of from about 600° to about 1300° F. with vaporized hydrogen fluoride in the presence of a high surface area contacting agent substantially inert to hydrogen fluoride.

2. A process for converting a hydrocarbon stream consisting essentially of paraffins having no more than four carbon atoms into middle distillate which comprises contacting a vaporized stream of said hydrocarbon in a reaction zone with vaporized hydrogen fluoride at a temperature of about 600° to about 1300° F. and at pressures from atmospheric to about 400 p.s.i.g. with high surface area activated carbon, and recovering a product comprising liquid acyclic hydrocarbons.

3. A process for converting propane into middle distillate which comprises contacting a vaporized stream consisting essentially of propane with gaseous anhydrous HF and activated carbon at a temperature of about 700 to about 1200° F. and at pressures of about atmospheric up to about 400 p.s.i.g., in a reaction zone, and recovering a liquid product containing isopentane.

4. A process for converting butane into middle distillate which comprises contacting a vaporized stream consisting essentially of butane with gaseous anhydrous HF and activated carbon at a temperature of about 700 to about 1200° F. and at pressures of about atmospheric up to about 400 p.s.i.g., in a reaction zone, producing hydrogen and liquid acyclic monoolefins boiling in the middle distillate range and withdrawing said liquid mono- 15

5. The process of claim 4 wherein a high quality middle distillate fuel is made by hydrogenating the liquid acyclic monoolefin product at least in part with the hydrogen so produced to obtain a saturated middle distillate fuel boiling in the range of about 200-600° F.

6. The process of claim 4 wherein the product comprises $C_{10}-C_{20}$ acyclic monoolefins.
